(57) **CLAIM**

The ornamental design for the portion of a retaining wall
block, as shown and described.

DESCRIPTION

FIG. 1 is a front perspective bottom view of the ornamental
portion of a retaining wall block;

FIG. 2 is a side elevational view of the portion of the central
portion of the retaining wall block of FIG. 1;

FIG. 3 is a front elevational view of the portion of the
retaining wall block of FIG. 1;

FIG. 4 is a top plan view of the portion of the retaining
wall block of FIG. 1;

FIG. 5 is a bottom plan view of the portion of the retaining
wall block of FIG. 1; and,

FIG. 6 is a rear elevational view of portion of the retaining
wall block of FIG. 1.

The broken lines showing the front and rear surface of the
portion of a retaining wall block are for illustrative purposes
only and form no part of the claimed design.
